UNITED STATES PATENT OFFICE.

ALFRED ALLEN, OF OAKLAND, CALIFORNIA.

WAVE-MOTOR.

No. 880,474.

Specification of Letters Patent.

Patented Feb. 25, 1908.

Application filed May 8, 1907. Serial No. 372,496.

To all whom it may concern:

Be it known that I, ALFRED ALLEN, a citizen of the United States, and a resident of Oakland, in the county of Alameda and State of California, have invented new and useful Improvements in Wave-Motors, of which the following is a specification.

This invention relates to improvements made in apparatus or devices for converting the power of the waves into rotary motion of a shaft to operate machinery, compress air, and perform other useful work. Apparatus for this purpose are generally embraced under the title of wave-motor.

15 The object of the invention is the production of an improved wave-motor, in which the combined motions of a floating hull or body as produced by the waves and the angular movements of pivoted booms or levers 20 on the hull or body and oscillated by the waves, are utilized and caused to give rotary motion of a shaft on the hull, and from which by suitable mechanical means power can be transmitted or applied to do useful 25 work.

To such end and object, chiefly, my invention comprises a novel construction and combination of hull or body, oscillating booms, or levers pivotally mounted on the 30 hull, and means for converting the movements of the booms or levers into rotary motion of a shaft.

The invention embraces, also, a novel wave-motor having a floating hull or body, a 35 rotatable shaft, mounted therein, booms or levers pivotally mounted on the hull for oscillating movement, and extending therefrom overboard into the surrounding body of water, and means mechanically connecting the 40 said booms with the rotatable shaft, whereby the motions of the hull or body and the movements of the booms will impart rotary motion to the shaft, all as hereinafter described and set forth.

45 The following description explains at length the nature of the said invention and the manner in which I proceed to produce, apply and carry out the same, the accompanying drawings referred to in the said description illustrating a wave-motor of my invention in its simplest form of its construction.

Figure 1 is a general view in side-elevation of a wave-motor of my invention, provided 50 with two booms or outriggers extending fore and aft; representing the apparatus as riding

at anchor and in operation. Fig. 2 is a longitudinal sectional-view, on an enlarged scale, of the hull or body and the mechanism mounted on it, the booms or levers being 55 broken off to bring the figure within the limits of the sheet. Fig. 3 is a horizontal section taken longitudinally through the hull or body; the latter being contracted in length, is of shorter dimensions longitudinally than the hull illustrated in Fig. 2. Fig. 4 is a vertical sectional-view taken transversely through the hull or body. Fig. 5 is a general plan or top-view of the motor apparatus shown in Fig. 1. Figs. 6 and 7 illustrate a 70 modification in which two sets of oscillating booms are arranged for operation on opposite sides of the hull at the bow and the stern; Fig. 6 being a longitudinal section of the bow-end, and Fig. 7 a plan or top-view of Fig. 6 75 parts being shown in section. Both these views are on an enlarged scale.

The hull or body indicated at *a* is closed in by a deck or top *b*, to provide water-tight compartments *c* for the machinery, and to 80 accommodate the necessary hands or workmen. The hull is also provided with wells or openings through the bottom, and also through the ends, as seen at *d*—*d*', proper strength and stiffness being secured by bulkheads and cross-braces.

In the well or open space *d*' that extends from the bow longitudinally inwards, is set or mounted on a pivot *e*, the part or member *f* which I have termed the boom. This part 90 of the apparatus consists of a lever arranged to work freely in a vertical arc on its pivot *e* and carrying a float or a counter weight on its outer end. A similar lever *g* in the opening *d*' on the bow is mounted on a pivot *h* 95 for oscillating movement in like manner to the first named lever *f*.

The terms "bow" and "stern" in this description are to be taken relatively, and not as indicating the actual bow and stern of the hull.

Extending from its pivot beyond the end of the hull each boom terminates at the outer end in a float *m*; and at the inner end, at or near the pivot it is provided with dogs or 105 pawls *p*—*p*', so attached to the boom on opposite sides of its pivot that the dogs will engage a ratchet-toothed wheel, or cog-wheel upon a shaft.

In the construction which I have illustrated in the drawings, the two oppositely placed booms *f* *g* are arranged in such man-

ner that the dogs on their ends will engage the teeth of the two cogwheels $n-n^1$, and the two wheels are in turn geared into a common shaft t through the medium of pinions $5-r-r^1$ on the axes $s-s^1$, and a spur-wheel w on the shaft t .

The pawls $p-p^1$ of each boom are held in working contact with their cogwheel by a weighted arm y placed on the opposite side 16 of the pivot of each dog. As these working parts are submerged when in operation, however, the means connecting the booms with the cogwheels should be of a strong and simple construction and with the view to 15 avoid the use of springs. In the mechanism herein employed, the pawls $p-p^1$ are so situated on opposite sides of the pivotal point of the boom that one pawl will catch and act on the wheel when the outer end of 25 the boom is ascending, or is thrown above the horizontal; whereas, the other pawl will act in the descending movement, with the effect to produce a continuous movement of the wheel in the same direction on its axis.

25 The shaft t to which the movements of the wheels $n-n^1$ are transmitted to produce rotary motion, is situated amidship, and the hull is so balanced or ballasted that the load will be equally distributed on opposite sides 30 of the center of the hull, thereby securing an even rocking or rolling motion of the hull in a fore and aft direction.

The pivotal points of the booms are situated also on opposite sides of, and equi- 35 distant from the center, and the length of the booms from the pivotal point to the float on the outer end should be calculated with the view to produce an even oscillation or movement of the hull on both sides of the 40 center. The shaft t is connected with or into the wheels $n-n^1$ by means of spur-gears and pinions, as shown.

It will be evident that the motion im- 45 parted to the shaft t may be transmitted or applied by various well-known mechanical means, to operate machinery, and do other work, as, for example, by fixing a sheave z on the shaft t to carry an endless wire cable, as illustrated in Fig. 3; or by connecting the 50 shaft of an air-compressing machine to the shaft t , and by that means compressing air in a tank by the power taken from the shaft.

The hull is controlled and maintained in proper working position with reference to 55 the currents and the direction of the waves by anchors and cables, usually attached to the forward boom; but attached as well at other points or parts of the apparatus where they will be found best adapted to maintain 60 the hull and the booms end on to the waves and currents.

The apparatus above described consisting of a hull divided longitudinally by central wells or compartments opening through the 65 bottom, and two longitudinally extending

booms, is the simplest form in which I have embodied my invention. It should be mentioned, however, that the number of booms may be increased and the hull be constructed with a greater number of openings for the 70 booms to work in; or a series or number of hulls of the construction illustrated in Figs. 1 and 5 may be coupled or connected together side by side to act on or operate a common shaft extending across or through the hulls. 75

In the modification which is illustrated in Figs. 6 and 7 the levers are arranged in pairs or couples on opposite sides of the hull, with those of the same pair extending fore and aft from the same pivotal point, so as to swing in 80 opposite arcs therefrom.

The shorter lever f^1 of each pair is keyed on the outer end of a solid rock-shaft 2 on the inner end of which is fixed the head 4 carrying the pawls $5-6$. The longer lever g^1 of 85 each pair is fastened on the outer end of a tubular shaft 3 , that has a similar head 7 carrying pawls $8-9$ secured on the inner end, as seen in Fig. 7. The two sets of pawls $5-6$, $8-9$ are under and in line with two toothed- 90 wheels $10-12$, that are mounted on and connected to a common shaft 13 by clutches of any well-known construction, so that each toothed wheel being actuated by its own lever and pawls may act separately on the shaft 95 13 to rotate the same without undue strain or tension on the shaft.

The motion of the shaft 13 is transmitted by gears and pinions $14-15$, 14^x-15^x to a shaft 16 carrying a sheave 17 for a transmit- 100 ting cable or chain-belt.

Having thus described my invention, what I claim and desire to secure by Letters Patent is:—

1. In a wave motor, the combination of a 105 hull, a lever pivotally mounted thereon for oscillatory movement in vertical planes and extending from the said pivot overboard, a shaft mounted in the hull, a toothed wheel thereon in close proximity to the pivoted end 110 of the lever, and pawls pivoted to the said lever on opposite sides of its pivot for engaging the toothed wheel and thereby moving the wheel by the oscillations of the lever.

2. In a wave-power the combination, of a 115 hull, a lever pivotally mounted on each end of the hull for oscillatory movement in an arc longitudinally of the hull, and extending from the said pivotal points fore and aft overboard; floats on the outer ends of the said 120 levers; pawls on the inner ends of the levers; and toothed wheels mounted on the hull in position to be engaged and rotated by the pawl-carrying ends of the levers.

3. The herein described wave-power com- 125 prising a hull; levers pivotally mounted on the hull for oscillatory movement in vertical arcs, said levers extending fore and aft beyond the hull, and having floats on their outer ends; toothed wheels mounted on the hull 130

for rotation in planes longitudinally of the hull; and means operatively connecting the inner ends of the levers with the toothed wheels, to rotate them from the oscillations of the said levers.

4. In a wave motor, the combination of a hull provided with a longitudinal opening extending from end to end thereof, booms pivotally mounted in said opening and ex-

tending fore and aft of the hull, a wheel rotatively mounted in the hull, and connections between the booms and the wheel for giving movement to the latter.

ALFRED ALLEN.
